United States Patent

Des. 240,267
Patented June 8, 1976

240,267

PIANO

Winsor D. White, Jr., Chicago, Ill., and Dennis Barket,
Cincinnati, Ohio, assignors to D. H. Baldwin Company,
Cincinnati, Ohio

Filed Aug. 26, 1974, Ser. No. 500,398

Term of patent 14 years

Int. Cl. D17—01

U.S. Cl. D56—9

FIG. 1

FIG. 2FIG. 3

FIG. 1 is a front, top and left side perspective view of a piano showing our new design;

FIG. 2 is a front elevational view; and

FIG. 3 is a right side elevational view.

The rear of the piano is conventional.

We claim:

The ornamental design for a piano, substantially as shown and described.
